UNITED STATES PATENT OFFICE.

JOHN CONRATH, OF CHICAGO, ILLINOIS.

DRAFT-RIGGING FOR RAILWAY-CARS.

SPECIFICATION forming part of Letters Patent No. 606,447, dated June 28, 1898.

Application filed March 28, 1898. Serial No. 675,354. (No model.)

To all whom it may concern:

Be it known that I, JOHN CONRATH, a citizen of the United States, residing at Chicago, county of Cook, and State of Illinois, have invented certain new and useful Improvements in Draft-Rigging for Railway-Cars, which are fully set forth in the following specification, reference being had to the accompanying drawings, forming a part thereof.

10 In the drawings, Figure 1 is a plan of my improved draft-rigging with tandem springs. Fig. 2 is a section at the line 2 2 on Fig. 1. Fig. 3 is a section at the line 3 3 on Fig. 1, the draw-bar, draft connections, and tandem springs 15 being removed. Fig. 4 is a section at the line 4 4 on Fig. 1. Fig. 5 is a section at the line 5 5 on Fig. 1. Fig. 6 is a plan of a draft-rigging comprising a portion of my invention having a single group of springs instead of 20 tandem springs.

In the drawings, A is the draw-bar.

K is a draft-loop which is connected at the forward end to the rear end of the draw-bar and encompasses the springs and their followers between the face and guide plates herein-after described.

B B are the draft-timbers.

C C are the longitudinal main sills above the draft-timbers, and C' is a cross-sill.

30 D is a spacing-block between the draft-timbers at the rear of the draft-rigging.

E is the draw-bar carrier or tie-bar connecting the draft-timbers at the forward end.

F is the bumper-sill at the forward end.

35 G G are face-plates for the draft-timbers and guide-plates for the followers.

H H and H' are followers for the springs, which in the form shown in the principal figures consist of two groups arranged tandem,

40 each group comprising a large spring J and a smaller spring J' within the large spring. Each couple or group of springs J and J' is lodged between one of the extreme followers H and the intermediate follower H'.

45 Each of the followers is provided with a central tongue h to center the inner springs J'. The outer springs are centered by virtue of their diameter being such that the space allowed them between the guide-plates G and between the

50 upper and lower sides of the draft-loop K is only sufficient to accommodate them. The rear end of the draw-bar is enlarged at A' to

form the shoulders a', which are engaged by the inwardly-turned ends K' K' of the draft-loop K, which is further secured to the draw-bar by riveted bolts k k. The face and guide plates G are let into the inner sides of the draft-timbers B B, and, in addition, the bosses for the horizontal bolts which bind them to the draft-timbers are further let into the timbers, as seen at b, Fig. 1, and to further increase the draft of the plates upon the draft-timbers, as well as to protect and stiffen the latter, the draft-plates have the upper and lower horizontal flanges G² and G³, for which gains are formed in the upper and lower sides of the draft-timbers. The draft-timbers are bound directly against the under sides of the sills C C by the bolts c c, and between the draft-timbers and sills, respectively, there are lodged the keys L L, for which suitable gains are formed in the under sides of the sills, and in the upper sides of the draft-timbers the upper flanges G² G³ of the plates G are apertured at g g g to admit the keys L, which thus operate against the edges of said apertures on the metal of the flanges of the face and guide plates, thereby further increasing the security of the draft connection thus made between the draft-timbers and the sills and taking the 55 shearing strain of the draft off the bolts c. The face-plates G have at their ends integral stops G⁴ G⁴ at front and rear, and at a distance inward from each of these extreme stops which is equal to the thickness of a follower H added 60 to the distance allowed for compression of the springs there is formed another integral stop G⁵. The intermediate follower H' is also lodged between stops G⁶ G⁶, separated by a distance equal to the thickness of the follower 65 H', added to the distance allowed for compression of the springs in both directions—that is, so that the follower may move in either direction from intermediate position the full distance necessary for compression of 70 the springs before encountering a stop in that direction. All these stops are integral ribs formed on the inner faces of the plates G. Conveniently the stops G⁵ and G⁶, between the extreme followers, respectively, and the 75 middle follower, are braced by the horizontal ribs g⁵ g⁵, which extend between them. At the upper edge each of the plates G has a 80 guide-flange G⁷ for followers, said guide-plates

extending between the stops, respectively, between which said followers are designed to travel. At the lower edge each plate has a channel or grooved flange G^8 , projecting to 5 the same distance as the guide-ribs and upper flanges; but this lower flange is cut away at the space opposite the guide-flanges G^7 G^7 G^7 , so that the flanges G^8 do not of themselves afford any guidance or support for the followers. 10 At the lower edge; but for this purpose I provide a bottom plate M , which is adapted to slide in the grooves g^8 of the lower flanges G^8 and afford suitable support for the followers. Each of the plates G has at the lower 15 rear corner a lug G^9 , having a bolt-hole g^9 , and the bottom plate M has corresponding lugs m , which, when said bottom plate is thrust into place, stand opposite the lugs g^9 g^9 , so that a simple key-bolt M' , inserted through 20 all the lugs and secured by a cotter-pin m' , serves to secure the bottom plate in place in such manner that the removal of the cotter-pin, permitting the withdrawal of the bolt, makes it possible for one man, unassisted, to 25 withdraw said bottom plate and remove the entire structure which is connected with the draw-bar which comprises the loop K and springs and followers encompassed by it. Whenever it is necessary to remove one of 30 the face-plates from the draft-bar, the interior structure being first withdrawn, as described, the outer ends of the bolts b' b' , by which the plates are bound to the draft-timbers, may be cut off and the bolts driven in- 35 ward into the space cavated by withdrawing the draw-bar loop-springs and followers, and in such case it will be noticed that the keys L L do not interfere with forcing off the face-plates, because they are lodged in notches in 40 the flanges of the face-plates and there are no bolts passing through these flanges. Similarly the lower flanges are notched for the bolts, as shown at g' .

In Fig. 6 I have shown similar detail features applied to a draft-rigging having a single group of springs. With the exceptions involved in the fact that there is only one group of springs the structure is the same, and in this case I have shown the key L 45 omitted at one of the bolts c , but the flange-plate G is notched to allow the plate to be driven off, as above described.

In both the forms illustrated—that is, whether a single group of springs or a plurality of such groups is employed—the space-block D is let into the facing sides of the draft-timbers, as seen in the drawings, and at the forward side abuts directly against the rear ends of the face-plates G , so that it affords additional security to the engagement of the face-plates with the draft-timbers in respect to the pushing movement which is transmitted through the draw-bar; and in order to facilitate the removal of this space-block when necessary for any purpose the bolts D' D' , which bind the draw-bars together into the space-block, instead of ex-

tending through the latter, as customary heretofore, extend behind it, so that upon being slacked to relieve the endwise pressure 70 upon the block the latter may be dropped or driven off from between the draft-timbers.

I claim—

1. In a draft-rigging for cars, in combination with the draft-timbers, a plurality of 75 groups of springs arranged tandem between the draft-timbers; followers between consecutive groups and beyond the extreme groups in both directions; the draw-bar adapted to abut against the nearest follower; a draft 80 connection therefrom extending beyond the most remote follower, and stops rigid with the draft-timbers to limit the inward movement of the extreme followers, each intermediate follower having a range of movement 85 in both directions from the position at which it is held by the springs when free from any action of the draw-bar, a distance equal to the compression for which the springs are calculated. 90

2. In a draft-rigging for cars, in combination with the draft-timbers, face-plates G let into the proximate faces of the timbers respectively and having horizontal flanges at top and bottom which are also let into the upper and lower sides of the timbers respectively; the draw-bar and draft connections therefrom between the face-plates comprising the springs and followers; the face-plates having rigid stops to limit the movement of 100 the followers. 95

3. In a draft-rigging for cars, in combination with the longitudinal sills; the draft-timbers and face-plates provided for the same having flanges extending over the upper surface of the draft-timbers, such flanges being let into said timbers, the flanges having notches; keys let into the lower side of the sills and upper side of the draft-timbers and extending through the notches in the flanges; 105 and bolts which bind the draft-timbers up against the under side of the sills. 110

4. In a draft-rigging for cars, in combination with draft-timbers, the face-plates made rigid therewith; the draw-bar and draft connection therefrom, and the springs and followers associated therewith between the face-plates; the ends of the followers extending laterally beyond the springs and stops and upper guides for said ends on the face-plates, 115 said face-plates having at their lower edges inwardly-projecting flanges cut away below the path of the followers respectively and provided with longitudinal inwardly-facing grooves between said cut-away portions; and a slide adapted to be inserted in such grooves 120 underneath the followers and springs, to afford lower support and guidance for the followers, and suitable key to retain such slide against longitudinal displacement. 125

5. In a draft-rigging for cars, in combination with draft-timbers, the face-plates made rigid therewith; the draw-bar and draft connections therefrom, and the springs and fol- 130

lowers associated therewith between the face-
plates; the ends of the followers extending
laterally beyond the springs and stops and
upper guides for said ends on the face-plates;
5 said face-plates having at their lower edges
flanges cut away below the path of the fol-
lowers respectively and provided with longi-
tudinal inwardly-facing grooves between said
cut-away portions; and a slide adapted to be
10 inserted in such grooves underneath the fol-
lowers and springs, and to afford lower sup-
port and guidance for the followers, said
face-plates having each an apertured lug

G⁹, and the slide having a correspondingly-
situated apertured lug whose apertures are 15
adapted to register with the apertures of the
lugs of the face-plates when the slide is in op-
erative position, and a suitable removable
key inserted through said apertures.

In testimony whereof I have hereunto set 20
my hand, in the presence of two witnesses, at
Chicago, Illinois, this 21st day of March, 1898.

JOHN CONRATH.
